PACKING

George T. Henderson, Sandusky, Ohio, assignor to
 The Hinde & Dauch Paper Company, Sandusky,
 Ohio, a corporation of Ohio

Application April 8, 1940, Serial No. 328,552

3 Claims. (CL. 206—46)

This invention relates to a reinforced packing case for packaging and shipping various articles of commerce and particularly intended for use in the furniture trade, whereby a corrugated board carton may be employed for packing such pieces of furniture or articles in the box in some definite and fixed position. For instance, the piece of furniture or article may be so located in the case that all finished surfaces are free from contact with the sides of the case, and such articles as need to be supported off the bottom and out of contact with the walls and top of the case may be so supported. Davenports, chairs, and tables are some examples of such pieces although these articles are merely exemplary since the invention is applicable to various other articles of furniture. The weight cannot be allowed to rest on the legs because of possibility of damage to the legs and to the furniture frame generally, and also because concentration of weight on the corrugated board at four small spots is undesirable. Various expedients are now employed to forestall this danger; for example one common means is to use a wood frame or saddle or other built-in structure of wood or fiberboard under the frame; or very thick pads of corrugated board are built up from the bottom of the case to the cross bars of the furniture to take the weight off the legs, and so on. One of the chief disadvantages lies in the fact that these prior devices are not sufficiently flexible to be used for a variety of different articles. Furthermore some previous methods require a different size box for each different sized article.

This invention aims to provide an interior support especially adapted to be used in large as well as small cases, particularly those made of corrugated board or similar materials, to avoid the difficulties outlined above. The invention is also particularly applicable as a top and bottom strengthening element in such packing cases, either with or without another such support intermediate the height of the case.

An example of a preferred embodiment of the invention is illustrated in the drawing and described in detail below, it being understood that the invention may be used in other forms applying the same principles, all within the scope of the claims.

In the drawing:

Fig. 1 is a perspective view of a case to which the invention is applied, the outside being partly broken away to show the interior better;

Fig. 2 is a transverse vertical section on plane 55

2—2 of Fig. 1, showing a davenport in dotted lines therein; and

Fig. 3 is an enlarged vertical section on plane 3—3 of Fig. 2, omitting the davenport.

The case shown in Fig. 1 is one suitable for a davenport 11, shown in dotted lines in Fig. 2 only, and comprises a corrugated board structure 12 having a top closure conventionally shown as consisting of inner part laps 13 at the ends and outer abutting half laps 14 at the sides, the joint of which may be taped according to the present practice, although the tape is not shown. The bottom closure is also conventional, and may conveniently be a repetition of the top.

My invention is shown applied as a supporting brace at 20 and as a top brace at 21. The members are attached the same way in both instances, and could be of identical construction, although in the present embodiment slight differences are illustrated between 20 and 21. Corresponding reference characters, distinguished by primes, are used for corresponding parts. End bars 22 and 25 are placed horizontally and edge up in corresponding inner and outer positions against walls such as the ends 23 of the case 12. The inner bars 22 have slats 24 fastened to their upper edges at appropriate spacing, as many slats being used as may be needed, and the length being enough to make a snug fit in the case. When the brace is in place the outer bars or clamps 25 are applied outside the respective end walls, opposite the inner bars 22, and fastened by screws 26 which pass through the end walls into the bars, Fig. 3. The screws are set up tight enough to pinch the corrugated board material of the ends 23, as shown in Fig. 3. The arrangement is the same at both ends. Although wood is illustrated as the preferable material for my improved brace other materials of construction, such as metal and bolts, are within the purview of the invention.

By reason of the clamping action, forces applied to the brace in any direction are distributed over a wide area of the case wall both inside and outside, and a tight and extensive frictional hold is given, which is aided by the shouldering effect on the corrugated board below the clamping bars, in addition to some support by the screw shafts through the wall 23.

50 A davenport 11 is indicated in dotted lines in Fig. 2, showing how such an article is placed with its frame 30 supported on the brace 20, which is spaced at a height from the bottom of the case 12 to clear the feet from the bottom. A chair or other article could be packed in similar manner,

of course placing the supports at suitable height. It will be understood by those skilled in the art that to hold such article entirely clear of the case walls the furniture could be secured to the slats 24 by screws or bolts into the underside of the furniture.

When placed at the top of the case, as 21, at the proper height to bring the slats 24 at the closing lever of the top, the brace strengthens the top and safeguards tops of large span from being broken in, as may occur when other freight is piled thereon. For this situation it is usually sufficient to use only one slat 24' at the top instead of two, in which event the inner and outer bars 22' and 25' will be materially shorter, for example $\frac{2}{3}$ the length of the corresponding lower pieces 22 and 25. If considered necessary, a brace, inverted, may be used in a similar manner to offer protection for the bottom of the case.

By my invention one size of carton can be used to pack a variety of different sizes of articles, thus reducing the number of different sizes of cartons that must be carried in stock by the shipper or manufacturer. A still further advantage is that the strips 25 on the outside of the box provide excellent handles making it unnecessary to cut hand holes in the box, apply metal or rope handles or the like, and that by such handles the support during carrying and handling is transmitted directly to the article rather than through the walls of the container.

Inasmuch as the top brace 24' supports the closure laps, such brace makes it possible to cement the laps 13, 14 shut instead of using tape or special stitching machines, which are more expensive than the use of adhesive. In addition, adhesive sealing results in a much more rigid box top because the inner and outer laps are bonded together over extensive areas, whereas when sealed with tape or stitching there is a certain amount of "weaving" or "wracking" of the box top resulting from movement between the inner and outer laps.

It will be seen from the foregoing that I have invented a packing device which is adapted to be used in corrugated board and like cartons of all sizes, and is particularly advantageous in large size cases, which requires no modification of ordinary carton shapes; which combines strength, simplicity, cheapness, ease of application and great strength; which distributes the load and so avoids concentrated stresses; which can readily be removed and re-used; which may easily be made with simple tools; requires no special skill for its assembly; may be made in a variety of detailed shapes and sizes; and which presents

other benefits and advantages, as will be apparent to those skilled in the art.

The foregoing detailed description and the drawing therewith are to be taken as illustrative and not limiting, the scope of the invention being set out in the following claims.

I claim:

1. A packing container of the class described, having walls of artificial fibrous board, means for holding an article inside of said container and out of contact with said walls, comprising longitudinally extending members and transversely extending end pieces for supporting said longitudinally extending members, means for connecting said end pieces to the walls of said container and to provide a handle on the outside of the container, said means comprising strips disposed on the outer wall of the container in opposing relation to said end pieces, and means extending through said walls and connecting the end pieces and strips together and adapted to clamp the container wall sufficiently tight between the strips and end pieces to slightly displace the material of the wall and distribute strains applied through the end pieces and strips to the wall over a large area of the wall.

2. In combination in a packing case having opposite walls of corrugated board, a brace comprising a tie with end supports transversely secured thereto, said supports being located on said opposite walls and each comprising an inner bar on the inner face of its respective wall and an outer bar opposite said inner bar but on the outer face of its respective wall, with fastenings clamping said bars together upon said wall and reducing the thickness of the corrugated board between the bars.

3. In combination with a packing container of fiber, corrugated board or the like, means for supporting an article in the container out of contact with the walls thereof and for bracing the container, comprising article supporting members disposed inside the container walls and means at each end of said members for supporting said ends each upon a wall in predetermined positions, each of said means including an inner member secured to said article supporting member and having a face transverse to said member and adapted for pressure against an inner face of a wall and an outer clamping member disposed against the outside of the same wall in opposed relation to said first-named face, and means interconnecting said face and said outer clamping member and securing them to each other and in clamping engagement with the wall.

GEORGE T. HENDERSON.
